TIE HOLDER CONSTRUCTION

Albert W. Lindquist, Edgewood, R. I., assignor to
Freeman Daughaday Company, a corporation of
Massachusetts

Application December 21, 1938, Serial No. 247,015

3 Claims. (Cl. 24—49)

My present invention relates to the jewelry art, and has particular reference to a novel construction for a tie holder.

It is the principal object of my invention to provide a tie holder construction having a minimum number of complicated working parts.

It is a further object of my invention to provide a tie holder construction with holding elements having a wide bearing for the tie parts.

10 It is a further object of my invention to provide a construction which is readily suitable for manufacture from stamped flat sheet stock and which is extremely easy to assemble.

A still further object of my invention is to provide a tie holder with resilient holding members which are readily slideable on and off a shirt and tie.

With the above and other objects and advantageous features in view, my invention consists of 20 a novel arrangement of parts more fully disclosed in the detailed description following, in conjunction with the accompanying drawing, and more specifically defined in the claims appended thereto.

25 In the drawing:

Fig. 1 is a plan view of a tie holder in use on a tie;

Fig. 2 is a side elevation of a tie holder embodying my invention;

30 Fig. 3 is a rear view thereof;

Fig. 4 is a side elevation of the pressure plate;

Fig. 5 is an enlarged rear view thereof;

Fig. 6 is a section taken along line 6—6 on Fig.

5;

35 Fig. 7 is a side elevation of a modified form of tie holder;

Fig. 8 is an enlarged rear view thereof;

Fig. 9 is an enlarged elevation, partly in section, of the pressure plate of the modified form shown 40 in Fig. 7; and

Fig. 10 is an enlarged rear view thereof.

It has been found desirable to provide a tie holder having an ornamental front portion and a rear portion which is resiliently urged towards the 45 front portion, with a pressure plate which is designed to spread the resilient action of the rear portion over a large surface so that the tie and shirt are held securely together without wrinkling, catching, or tearing of the shirt or tie. I have 50 further provided for a minimum number of parts which can be readily stamped from sheet stock and easily assembled.

Referring to the drawing, the novel tie holder 55 includes a front portion 21 which may be of any desired shape and which may be ornamented

in any suitable manner. The front portion 21 is preferably formed of elongated sheet stock to extend across the front of the tie, as shown in Fig. 1, and is reentrantly bent at one end to form a resilient loop 22 and a spring tongue 23 which extends in adjacent relation to the front portion 21 and preferably towards it, as shown in Fig. 2. Between the spring tongue 23 and the front portion 21 is a pressure element 24 which is preferably in the form of a plate and urged towards resilient 10 engagement with the rear of the front portion 21 by the pressure from the free end of the spring tongue 23.

The pressure plate 24 may be of solid construction but is preferably stamped from sheet stock in the manner shown in Figs. 4, 5 and 6. The pressure plate 24 is preferably of the same width as the front portion 21 and is of sufficient length to extend substantially across the entire back of the front portion 21, and is formed of sheet stock 20 which is turned at the edges to form upturned flanges 25 extending across the length of the pressure plate on each edge thereof. The front of the pressure plate is turned sharply upward, as at 26, and the upturned flanges from the front 25 portion slope upwardly to form a substantially wide portion 27. The rear of the pressure plate is also turned upwardly, as at 27, but not as sharply as the front portion 26 and the flanges slope gradually upwardly to meet the upwardly 30 sloped front flanges and to form a platform 29 and an abrupt abutment 30 where they join the wide portion 27 of the front flanges.

On the platform 29 is a rectangular block 31 formed from the sheet stock, as shown in Figs. 4 35 and 5. The height of the block 31 and of the abutment 30 is substantially equal to the thickness of the front portion 21.

In assembling the tie holder, the resilient rear tongue 23 is forced away from the front portion 21 and the pressure plate is slipped beneath it as shown in Fig. 2. A non-circular, preferably rectangular opening 32, near the end of the spring tongue 23, is allowed to slip over the correspondingly shaped block 31 as shown in Fig. 3, thus providing a loose connection; the pressure plate 24 will then be urged resiliently against the rear of the front portion 21 by the pressure of the spring tongue 23. Furthermore, the journalling of the rectangular block 31 in the rectangular opening 32 prevents swerving or sideways movement of the pressure plate when in use. The upwardly inclined front flange on the pressure plate, forming the wide portion 27, forms a line with the surface of the tongue 23, as shown in Fig. 2 so that 50 55

no abutment or obstruction, tending to catch in the wearer's clothing, appears. The upturned front portion of the pressure plate, at 26, permits the pressure plate to ride easily over the shirt, the 5 loose connection permitting a slight turning, and the upturned end 28 in the rear of the pressure plate permits removal of the tie holder without catching on the clothes of the wearer.

The construction heretofore described, while 10 preferably stamped from sheet stock, can readily be made from solid material. When cast from solid material, the form shown in Figs. 7 to 10 inclusive may be used. In this form the side flanges of the pressure plate 33 may be extended across 15 the platform portion 34 to form flanges 35 and 36 on each side of the block 37. With this construction, when the pressure plate is placed beneath the spring tongue 38, the spring tongue 38 nests between the sides of the flanges 35 and 36 20 and is hidden from view from the side, as shown in Fig. 7. This arrangement further tends to eliminate the possibility of the tie holder's catching on the tie or the shirt.

A large surface is thus provided by the pressure plate to grip the shirt and tie together, without creasing or indenting the tie or shirt in any manner. By using a fairly heavy stock, the spring loop 22 and spring tongue 23 may be made fairly 25 stiff so that a heavy spring resilient action is obtained. This can readily be done with the present construction because the shape of the pressure plate facilitates sliding of the tie holder, regardless of the strength of the spring action, both on and off the tie and shirt. The above 30 described construction is very easy to manufacture and can be readily assembled without the use of tools or special skill.

While I have described a specific constructional embodiment of my invention, any desired 35 changes in the size of the parts, in the materials used for the parts, and in the shape and ornamentation of the parts may be made to suit requirements for different tie holder designs with-

out departing from the spirit and the scope of the invention as defined in the appended claims.

I claim:

1. In a tie holder construction comprising a front member, a rear member integral with and resiliently urged towards said front member, and a pressure element between the two members, said pressure element comprising a pressure plate adapted to be interposed between the front and rear members whereby said rear member resiliently urges said plate towards said front member, said pressure plate having a non-circular block, said rear member having a non-circular opening adjacent the free end thereof, said block being journaled in said opening. 15

2. In a tie holder construction comprising a front member, a rear member integral with and resiliently urged towards said front member, and a pressure element between the two members, said pressure element comprising a pressure plate 20 adapted to be interposed between the front and rear members whereby said rear member resiliently urges said plate towards said front member, said pressure plate having an integral rectangular block, said rear member having a rectangular opening adjacent the free end thereof, 25 said block being journaled in said opening.

3. In a tie holder construction comprising a front member, a rear member integral with and resiliently urged towards said front member, and a pressure element between the two members, said pressure element comprising a pressure plate 30 adapted to be interposed between the front and rear members whereby said rear member resiliently urges said plate towards said front member, said pressure plate having a housing comprising three side walls and an open front and an integral rectangular block in said housing, 35 said rear member having a rectangular opening adjacent the free end thereof, said block being journaled in said opening. 40

ALBERT W. LINDQUIST.
